UNITED STATES PATENT OFFICE.

NELLIE C. JACKSON, OF CHICAGO, ILLINOIS.

COLLAPSIBLE RECEPTACLE.

1,286,009.

Specification of Letters Patent.

Patented Nov. 26, 1918.

Application filed February 9, 1917. Serial No. 147,525.

To all whom it may concern:

Be it known that I, NELLIE C. JACKSON, a citizen of the United States of America, and resident of Chicago, in the county of Cook 5 and State of Illinois, have invented certain new and useful Improvements in Collapsible Receptacles, of which the following specification, together with the accompanying drawings, is a full and clear disclosure.

10 My invention relates to collapsible receptacles.

Among the objects of my invention are the following:

To provide a box which, although it may 15 be utilized for a variety of purposes, is especially adapted for protecting hats and the like. In other words, it is especially adapted for storing objects during a trip, for example, which objects ordinarily are 20 liable to be easily crushed or disfigured.

To provide a receptacle which may be easily folded up and tucked away; that is, one which is not cumbersome.

To provide such receptacle of good appearance when opened up for use, and handy so that the object or objects to be protected 25 may be put in place without difficulty.

To provide a novel arrangement of the links which form the frame of the receptacle, and to provide a novel arrangement of the covering.

It is also an object to provide certain details and features of improvement tending to increase the efficiency and serviceability of 35 the collapsible receptacle.

The means for accomplishing the foregoing and other useful ends are hereinafter more particularly set forth and claimed.

Referring to the drawing it will be seen 40 that it shows the receptacle in perspective, the top of the receptacle being provided with a hook for hanging purposes.

Referring more in detail to the structure, it will be seen that it comprises a square top 45 central plate A, from each of the four sides of which project sets of arms a, from each of which sets there extends a pin b. Each of these pins passes through the eye of a link of which there are four, to wit: B', B², B³ and 50 B⁴. Each of these links terminates at the lower end in an eye, each of which eyes is threaded by a ring, there being therefore, four rings in all, pointed out by the characters c', c², c³, and c⁴. It will be observed that

the link C' which is provided with an eye at 55 each end is threaded at one end by the ring c' and is threaded at the other end by the link B². Similarly the link C² is threaded by the ring c² at one end and by the link B⁴ at the other. In the same fashion the link C³ is 60 threaded at one end by the link c³ and at the other end by the link B', and in a similar manner the link C⁴ is threaded at one end by the link c⁴ and at the other end by the link B³. 65

Therefore, it will be seen that by sliding the end of the link C', which is threaded by the link B², upwardly along the link B², and by sliding the end of the link C² in a similar manner along the link B⁴, and the end of the 70 link C³ along the link B', and the end of the link C⁴ along the link B³, the frame can be folded up so as to form a bundle of parallel links. In this condition it occupies very little space and may be tucked away any- 75 where, in a grip or a trunk, or the like.

Now in connection with this structure I provide a covering having four sides resembling a pyramid somewhat, and a bottom. There is also provided a top side which 80 makes the whole resemble a pyramid with the top cut off. Now, this covering I propose to make of either cloth or tar paper or any other material that may be suitable for the purpose. As shown in the drawing one 85

of the sides of the covering is arranged so that it may be buttoned up after the hat or other object has been slipped into the box, and so that it may be unbuttoned when the object is to be taken out. Instead of buttons, of course, glove fasteners or other type of fastening device may be used. In the drawing the lap that might be called the door of the device is shown down. Although I have shown only one door it is perfectly obvious that I can arrange a door on one or more of the other sides, or, if it is so desired, the opening can be made in the bottom. It will be understood that this covering is made of such size that when the 100 frame is inserted in the covering and opened up it will fit the frame snugly and contribute toward holding the frame in position. This arrangement, of course, is not absolutely essential, since the frame can be made 105 to stand out regardless of the covering if desired.

It will be understood that the receptacle

may be folded up with the covering still in place, or it can be removed from the covering.

- On the top of the frame, as has already 5 been pointed out, there is provided a hook D, which may be used for hanging the receptacle. This hook, of course, may be made to screw into the block A, and may be put in position after the frame is in place, in which 10 case only a very small opening is necessary in the top of the covering, otherwise an opening large enough must be provided in the top of the covering to permit the hook to pass through.
- 15 It will be understood that one or more of the sides of the device I propose to utilize for advertising purposes as indicated in the drawing.

It may sometimes be advisable to have 20 the envelop attached to the lower part of the collapsible frame so that the envelop may not fall away from the frame. In other words it may be desirable to secure the ends of the frame to the corners of the envelop 25 so that even when the structure is folded the parts will retain their operative relation in order that when the device is to be opened the opening may be accomplished with the greatest convenience. If the envelop is made 30 of cloth this may be done through the medium of tape T that may be in any manner suitably secured to the envelop. Or I may even provide eyelets in the neighborhood of the interlocking links C', C², etc., through 35 which a string may be threaded after which the envelop may be tied to the ring. This arrangement will serve just as well regardless of the material used for the envelop, whether paper or anything else. This latter 40 arrangement is shown in the drawing.

What I claim as my invention is:

1. In a frame for a collapsible box consisting of a main plate, a plurality of members hinged thereto and extending therefrom each terminating in an end to which there is suitably pivoted an auxiliary link, each of said auxiliary links terminating in a suitable end and held in engagement with one of the other of said first extending members whereby the said last mentioned end may be slid back and forth along the said associated first extending member, whereby the frame may be folded or opened up at will.

2. In a frame for a collapsible box consisting of a main plate, a plurality of members hinged thereto and extending therefrom each terminating in an end to which there is suitably pivoted an auxiliary link, each of said auxiliary links terminating in a suitable end and held in engagement with one of the other of said first extending members whereby the said last mentioned end may be slid back and forth along the said associated first extending member, whereby

the frame may be folded or opened up at will, and a hanging hook for supporting the whole device, said hook attached to said plate.

3. In a frame for a collapsible box consisting of a main plate, a plurality of members hinged thereto and extending therefrom each terminating in an end to which there is suitably pivoted an auxiliary link, each of said auxiliary links terminating in a suitable end and held in engagement with one of the other of said first extending members whereby the said last mentioned end may be slid back and forth along the said associated first extending member, whereby the frame may be folded or opened up at will, and an envelop for receiving said frame whereby the envelop may be maintained extended for use.

4. In a frame for a collapsible box consisting of a main plate, a plurality of members hinged thereto and extending therefrom each terminating in an end to which there is suitably pivoted an auxiliary link, each of said auxiliary links terminating in a suitable end and held in engagement with one of the other of said first extending members whereby the said last mentioned end may be slid back and forth along the said associated first extending member, whereby the frame may be folded or opened up at will, a hanging hook for supporting the whole device, said hook attached to said plate, an envelop for receiving said frame whereby the envelop may be maintained extended for use, and a flap on said envelop serving as a door whereby articles may be deposited in the envelop.

5. In a frame for a collapsible box consisting of a main plate, a plurality of members hinged thereto and extending therefrom each terminating in an end to which there is suitably pivoted an auxiliary link, each of said auxiliary links terminating in a suitable end and held in engagement with one of the other of said first extending members whereby the said last mentioned end may be slid back and forth along the said associated first extending member, whereby the frame may be folded or opened up at will, a hanging hook for supporting the whole device, said hook attached to said plate, an envelop for receiving said frame whereby the envelop may be maintained extended for use, a flap on said envelop serving as a door whereby articles may be deposited in the envelop, and fastening means on said flap and on the main portion of said envelop whereby the envelop may be closed up.

6. In a frame for a collapsible box consisting of a main rectangular plate, a plurality of members radiating therefrom, one from each side of the plate each terminating in an end to which there is suitably pivoted

- through the medium of an interlocking ring an auxiliary link, each of said auxiliary links terminating in a suitable end and held in engagement with one of the other of said 5 first extending members whereby the said last mentioned end may be slid back and forth along the said associated first extending member, whereby the frame may be folded or opened up at will.
- 10 7. In a frame for a collapsible box consisting of a main rectangular plate, a plurality of members radiating therefrom, one from each side of the plate each terminating in an end to which there is suitably pivoted 15 through the medium of an interlocking ring an auxiliary link, each of said auxiliary links terminating in a suitable end and held in engagement with one of the other of said first extending members whereby the said 20 last mentioned end may be slid back and forth along the said associated first extending member, whereby the frame may be folded or opened at will, said auxiliary links forming, when the device is opened, a 25 rectangle.
8. In a frame for a collapsible box consisting of a main rectangular plate, a plurality of members radiating therefrom, one from each side of the plate each terminating in an end to which there is suitably pivoted 30 through the medium of an interlocking ring an auxiliary link, each of said auxiliary links terminating in a suitable end and held in engagement with one of the other of said 35 first extending members whereby the said last mentioned end may be slid back and forth along the said associated first extending member, whereby the frame may be folded or opened up at will, said auxiliary links forming, when the device is opened, a rectangle.
- 40 9. In a frame for a collapsible box consisting of a main rectangular plate, a plurality of members radiating therefrom, one from each side of the plate each terminating in an end to which there is suitably pivoted 45 through the medium of an interlocking ring an auxiliary link, each of said auxiliary links terminating in a suitable end and held 50 in engagement with one of the other of said first extending members whereby the said last mentioned end may be slid back and forth along the said associated first extending member, whereby the frame may be folded or opened at will, an envelop for receiving said frame and whereby the envelop may be maintained extended for use, said auxiliary links forming, when the device is opened, a rectangle.
10. In a frame for a collapsible box consisting of a main rectangular plate, a plurality of members radiating therefrom, one from each side of the plate each terminating in an end to which there is suitably pivoted 55 through the medium of an interlocking ring an auxiliary link, each of said auxiliary links terminating in a suitable end and held 60 in engagement with one of the other of said first extending members whereby the said last mentioned end may be slid back and forth along the said associated first extending member, whereby the frame may be folded or opened at will, an envelop for receiving said frame and whereby the envelop may be maintained extended for use.
11. In a frame for a collapsible box consisting of a main rectangular plate, a plurality of members radiating therefrom, one from each side of the plate each terminating in an end to which there is suitably pivoted 65 through the medium of an interlocking ring an auxiliary link, each of said auxiliary links terminating in a suitable end and held 70 in engagement with one of the other of said first extending members whereby the said last mentioned end may be slid back and forth along the said associated first extending member, whereby the frame may be folded or opened at will, an envelop for receiving said frame and whereby the envelop may be maintained extended for use, said auxiliary links forming, when the device is opened, a rectangle.
12. In a frame for a collapsible box consisting of a main rectangular plate, a plurality of members radiating therefrom, one from each side of the plate each terminating in an end to which there is suitably pivoted 75 through the medium of an interlocking ring an auxiliary link, each of said auxiliary links terminating in a suitable end and held 80 in engagement with one of the other of said first extending members whereby the said last mentioned end may be slid back and forth along the said associated first extending member, whereby the frame may be folded or opened at will, an envelop for receiving said frame and whereby the envelop may be maintained extended for use, said auxiliary links forming, when the device is opened, a rectangle.
13. In a frame for a collapsible box consisting of a main rectangular plate, a plurality of members radiating therefrom, one from each side of the plate each terminating in an end to which there is suitably pivoted 85 through the medium of an interlocking ring an auxiliary link, each of said auxiliary links terminating in a suitable end and held 90 in engagement with one of the other of said first extending members whereby the said last mentioned end may be slid back and forth along the said associated first extending member, whereby the frame may be folded or opened at will, an envelop for receiving said frame and whereby the envelop may be maintained extended for use, said auxiliary links forming, when the device is opened, a rectangle.
14. In a frame for a collapsible box consisting of a main rectangular plate, a plurality of members radiating therefrom, one from each side of the plate each terminating in an end to which there is suitably pivoted 95 through the medium of an interlocking ring an auxiliary link, each of said auxiliary links terminating in a suitable end and held 100 in engagement with one of the other of said first extending members whereby the said last mentioned end may be slid back and forth along the said associated first extending member, whereby the frame may be folded or opened at will, an envelop for receiving said frame and whereby the envelop may be maintained extended for use, said auxiliary links forming, when the device is opened, a rectangle.

Signed by me at Chicago, Cook county, Illinois, this 1st day of February, 1917.
NELLIE C. JACKSON.
